COMBINED DRIER AND SPACE HEATER

Rallston M. Sherman, Glastonbury, Conn., assignor to
The Silent Glow Oil Burner Corporation, Hartford,
Conn., a corporation of Connecticut

Application June 29, 1956, Serial No. 42,089

Term of patent 14 years

(Cl. D81—10)

Fig. 1.

Fig. 2.

Fig. 3.

Fig. 4.

Fig. 1 is a front elevational view of a combined drier and space heater, showing my new design;

Fig. 2 is a rear elevational view;

Fig. 3 is an end elevational view; and

Fig. 4 is an opposite end elevational view.

I claim:

The ornamental design for a combined drier and space heater, substantially as shown.
